DESIGN FOR A DUST REMOVER

Curtiss F. Smith, West Hartford, Conn.

Application August 20, 1937, Serial No. 71,214

Term of patent 3½ years

To all whom it may concern:

Be it known that I, Curtiss F. Smith, a citizen of the United States and a resident of West Hartford, in the county of Hartford and State of Connecticut, have invented a new, original, and ornamental Design for a Dust Remover, of which the following is a specification, reference being had to the accompanying drawing, forming part thereof, in which—

Figure 1 is a view in side elevation of a dust remover embodying my new design.

Figure 2 is an end view.

Figure 3 is a bottom plan view.

The characteristic features of my design reside in a dust remover having a backing of the configuration shown in plan view and having a cen-

tral top flat portion merging gradually into curved end portions with a marginal bead surrounding the base of the back, the bottom face of said dust remover being characterized by four reversely curved ribs extending short of the full length thereof and within said bead and a pair of relatively short curved ribs respectively disposed at each side of the bottom face near the diagonally opposite corners thereof and set into the concaved sides of the adjacent reversely curved ribs as shown.

I claim:

The ornamental design for a dust remover, as shown and described.

CURTISS F. SMITH.
